US00D835172S

(12) **United States Design Patent** (10) Patent No.: **US D835,172 S**
Fujita et al. (45) Date of Patent: ** Dec. 4, 2018

(54) **DIGITAL CAMERA**

(71) Applicant: **Nikon Corporation**, Tokyo (JP)

(72) Inventors: **Chikara Fujita**, Tokyo (JP); **Hiroyuki Asano**, Tokyo (JP)

(73) Assignee: **Nikon Corporation**, Tokyo (JP)

(**) Term: **15 Years**

(21) Appl. No.: **29/633,419**

(22) Filed: **Jan. 13, 2018**

Related U.S. Application Data

(63) Continuation of application No. 29/569,142, filed on Jun. 23, 2016.

CLAIM

The ornamental design for a digital camera, as shown and described.

DESCRIPTION

FIG. 1 is a front, top and right side perspective view of a digital camera showing our new design;
FIG. 2 is a rear, bottom and left side perspective view thereof;

FIG. 3 is a front elevational view thereof;

FIG. 4 is a rear elevational view thereof;

FIG. 5 is a top plan view thereof;

FIG. 6 is a bottom plan view thereof;

(Continued)

FIG. 7 is a right side elevational view thereof; and, FIG. 8 is a left side elevational view thereof. The broken lines illustrate portions of the digital camera and form no part of the claimed design. The dash dotted lines denote the boundaries of the claim and form no part of the claimed design.

1 Claim, 8 Drawing Sheets
